UNITED STATES PATENT OFFICE.

JOSEPH C. TYLER, JOHN A. BEHRENDTS, AND LAKE PARKS, OF ABILENE, TEXAS.

MACHINE FOR TRUING LOCOMOTIVE DRIVING-WHEELS.

1,085,710.

Specification of Letters Patent.

Patented Feb. 3, 1914.

Application filed March 15, 1913. Serial No. 754,648.

To all whom it may concern:

Be it known that we, JOSEPH C. TYLER, JOHN A. BEHRENDTS, and LAKE PARKS, citizens of the United States, residing at Abilene, in the county of Taylor and State of Texas, have invented certain new and useful Improvements in Machines for Truing Locomotive Driving-Wheels, of which the following is a specification, reference being had to the accompanying drawings.

This invention relates to new and useful improvements in machines for truing the driving wheels of locomotives; but we do not wish to be limited in the application of our invention to that particular use, as it will be obvious that there are other uses to which it could be advantageously applied, for instance, as truing freight car wheels or similar truck wheels, etc.

20 The object of our invention is to provide a machine of this character which is adapted to be applied to the track rails and operated upon each wheel separately after the same has been jacked up sufficiently to clear the track, thus obviating the necessity of removing the wheels from the locomotive.

It is the general practice at the present time, when wheels become flat or worn so as to be irregular, to remove the wheels from the engine and put them in a lathe for the purpose of truing the tread and flange. It is obvious that such methods are expensive. In our device, an engine may be run into a round house or repair shop where power 35 may be obtained, the device clamped to the rail and the wheel jacked up to clear the track, the power is then applied and the wheel is turned and trued at one operation.

Another object of the invention is to provide a machine of this character which will possess advantages in points of efficiency and durability, is inexpensive of manufacture and at the same time is simple in construction and operation.

45 With the above and other objects in view, the invention consists in the novel features of construction and the combination and arrangement of parts hereinafter more fully described, pointed out in the claim and 50 shown in the accompanying drawings, in which—

Figure 1 is a side elevation illustrating the application of our improved machine for truing the driving wheels of locomo-

tives; Fig. 2 is a top plan view; Fig. 3 is a vertical sectional view; Fig. 4 is a transverse sectional view; and Fig. 5 is a longitudinal sectional view illustrating the application of our machine to the top of a rail.

Referring more particularly to the drawings, 1 indicates the body member of the machine which is constructed of steel or other suitable metal and bifurcated at its lower end as shown at 2 to form two oppositely disposed members 3 which are adapted to be arranged upon opposite sides of the tread of the rail and rigidly secured thereto by means of the tapering wedge members 4. The wedge members are driven in between the tread of the rail and the inner walls of the members 3, each of said wedge members being driven in from opposite directions, so that they will securely clamp the body member to the rail, it being apparent that the main portion of the body 1 will rest upon the upper face of the tread. The body member 1 is provided with the transverse opening 5 in which is mounted a power shaft 6, having the worm gears 7 and 8 mounted thereon and disposed upon opposite sides of the body. It will be understood that the shaft 6 may be driven by any suitable form of motor (not shown).

Secured to each side of the body member 1 and arranged adjacent the front and rear sides thereof are the bearings 9 in which are mounted the shafts 10 which are adapted to be disposed at an angle with respect to the body as clearly shown in Fig. 90 1. Mounted upon the outer ends of the shafts 10 are the corrugated rollers 11 which are adapted to engage upon the opposite sides of the flange of the wheel to rotate said wheel when motion is imparted to the shafts. Mounted upon the intermediate portions of the shafts 10 are the gears 12 which are adapted to mesh with the worm gears 7 and 8 upon the power shaft 6 to impart motion to the rollers 11.

100 Mounted upon the upper end of the body member is a bearing plate 13, which is provided with a centrally arranged opening 13' in which is rotatably mounted the downwardly extending lug 14 which is formed integral upon the under side of the elongated plate 14'. The ends of the bearing plate 13 are provided with the enlarged

portions 15 having the arcuate undercut side walls 16 formed in the inner faces thereof, said undercut side walls being adapted to receive the tapering arcuate ends 5 of the plate 14'. Formed upon the upper face of the plate 14' is an elongated enlarged portion 17 which is provided with a centrally arranged groove 18 closed at one end as shown at 19. Slidably mounted 10 upon the enlarged portion 17 is an adjustable block 17' having undercut side walls 18' adapted to receive the tapering side edges of the enlarged portion 17. Formed integral with the under side of the block 17' 15 is an apertured lug 19' which is disposed within the groove 18. A longitudinal screw 20 is mounted in a suitable bearing 21' which is arranged within the closed end 19, the inner end of said screw being mounted 20 in the apertured lug 19' whereby the block 17' may be laterally adjusted with respect to the periphery of the locomotive wheel. Secured to the outer end of the screw 20 is 25 a handle member 22' whereby the screw may be readily manipulated to adjust the block 17'.

The elongated plate 14' is provided at one end and upon the under surface thereof with the serrations 19^a which are adapted to be 30 engaged by the worm gear 20^a mounted upon the transverse shaft 21^a whereby the plate 14' may be readily rotated. A suitable handle member 22^a is mounted upon the outer end of the shaft 21^a by means of which 35 the shaft may be readily rotated to adjust the plate 14'.

The tool standard 23 is carried by the central portion of the block 17' and adjustably mounted therein is a shank 24, said 40 shank being held in various adjusted positions by means of the set screw 25 carried by the standard 23. Adjustably secured within the outer end of the shank 24 is a cutting knife 26, which is held in various adjusted 45 positions by means of the set screw 27. Thus as the wheel is turned by means of the corrugated rollers 11, the cutting knife 26 can be readily adjusted to various positions so that the uneven surface of the tread of the 50 wheel may be readily evened off.

Secured to one end of the bearing plate 13 and extending upwardly from the body in a substantially vertical position is a brace member 28, the upper end of which is securely bolted by means of the bolts 29 to one 55 of the longitudinal arms of the bracing frame 30. Securely bolted to the frame 30 is a supporting plate 31.

The numeral 32 indicates the trunnion of 60 a locomotive drive wheel having a brass bearing 33 arranged upon the upper side thereof and a supporting block 34 is arranged beneath the same and spaced from the trunnion by means of the babbitt 35,

which forms a suitable bearing for the trunnion 32. Arranged between the plate 31 and the block 34 are the wedge members 36 which are driven in securely to rigidly support the trunnion.

In Fig. 1, we have illustrated suitable 70 means for automatically adjusting the block 17' which carries the cutting tool 26. This means comprises a universal shaft 37 mounted in suitable bearings 38 which are secured to the side of the body member 1. Mounted 75 upon the shaft 37 is a gear 39 which is adapted to mesh with the worm gear 40 mounted upon one of the shafts 10. Mounted upon the upper end of a shaft 37 is a worm gear 41, said worm gear meshing with 80 a suitable gear 42 mounted upon the outer end of the screw 20. When the block 17' is in a position wherein the apertured lug 19' is at the outer end of the screw 20, the worm gear 41 is engaged with the gear 42 by means 85 of the bell crank lever 43 which is mounted upon the end of the bearing plate 13. From the above, it will be seen that the block 17' may be readily and quickly adjusted by engaging the worm gear 41 with the gear 42. 90

From the above description taken in connection with the accompanying drawings, it will be readily apparent that we have provided an improved machine for turning and truing locomotive drive wheels at one operation. 95

In the practical use of our invention, the locomotive wheel is first jacked up clear of the track and the body member 1 is then securely clamped to the tread of the wheel beneath one side of the wheel, power is then supplied to the shaft 6, which in turn will transmit motion to the corrugation rollers 11 to rotate the wheel. The knife 26 is then moved toward the periphery of the wheel 105 and adjusted to any desired angle so that the uneven surface of the tread of the wheel may be readily removed therefrom.

It will be readily apparent that in using our improved machine, the body 1 is securely 110 clamped to one of the rails beneath one of the driving wheels of the locomotive. After the uneven surface of the tread of this wheel has been removed, the body is released from the track and placed beneath the wheel upon 115 the opposite side of the locomotive and readily secured to the track rail to hold the same against movement, while removing the uneven surface of the second wheel. It will also be apparent that the device is extremely 120 simple in construction and at the same time can be manufactured at a comparatively low cost.

While we have shown and described the preferred form of our invention, it will be 125 obvious that various changes in the details of construction and in the proportions may be resorted to for successfully carrying our in-

vention into practice, without sacrificing any of the novel features or departing from the scope of the appended claim.

What we claim is:—

- 5 In a device of the character described, the combination of a body member, means for securing said body in a rigid position, a driving shaft mounted in said body, angular shafts disposed upon opposite sides of the
- 10 body, means for connecting said shafts with the power shaft, corrugated rollers mounted upon the upper ends of the angularly disposed shafts and adapted to engage opposite

sides of a wheel to rotate the same, and a cutting tool adjustably mounted upon said body 15 and adapted to engage the periphery of the wheel.

In testimony whereof we hereunto affix our signatures in the presence of two witnesses.

JOSEPH C. TYLER.
JOHN A. BEHREND'S.
LAKE PARKS.
